UNITED STATES PATENT OFFICE.

EDWARD BEACH GALLAHER, OF PHILADELPHIA, PENNSYLVANIA.

DESIGN FOR A MOTOR-VEHICLE FRAME.

SPECIFICATION forming part of Design No. 34,577, dated May 28, 1901.

Application filed April 13, 1901. Serial No. 55,796. Term of patent 7 years.

To all whom it may concern:

Be it known that I, EDWARD BEACH GALLAHER, a citizen of the United States, and a resident of Philadelphia, in the county of Philadelphia and State of Pennsylvania, have invented and produced a new and useful original Design for a Motor-Vehicle Frame, of which the following is a specification, reference being had to the accompanying drawings, forming a part thereof.

Figure 1 is a plan view of the motor-vehicle frame. Fig. 2 is a side view of the same, and Fig. 3 is a transverse section taken in the plane of the line 3 3 of Fig. 1 looking in the direction of the arrow.

As shown in the drawings, the leading or material feature of my design is in the configuration of a motor-vehicle frame formed by side bars *a* and *b*, having their front ends connected to the front cross-bar *c* at points a short distance inwardly from its ends, the

rear ends of the said side bars being provided with independent T-shaped rear-axle bearings *d* and *e*, the said side bars being further connected by a cross-bar *f*, adjoining the rear-axle bearings *d* and *e*, and a cross-bar *g*, spaced a distance therefrom, the said side bars *a* and *b* being drawn inwardly a slight distance toward each other between the cross-bar *g* and the front cross-bar *c*.

30

What I claim is—

The design for a motor-vehicle frame, substantially as herein shown and described.

In testimony that I claim the foregoing as my invention I have signed my name, in presence of two witnesses, this 8th day of April, 1901.
